[57] CLAIM

The ornamental design for a vaporizer, as shown and described.

DESCRIPTION

FIG. 1 shows a front, top and right side perspective view of a vaporizer incorporating our new design;

FIG. 2 shows a front elevational view of the vaporizer shown in FIG. 1;

FIG. 3 shows a rear elevational view of the vaporizer shown in FIG. 1;

FIG. 4 shows a right side elevational view of the vaporizer shown in FIG. 1; the left side elevational view being a mirror image of the right side elevational view;

FIG. 5 shows a top plan view of the vaporizer shown in FIG. 1; and,

FIG. 6 shows a bottom plan view of the vaporizer shown in FIG. 1.

The broken line showing of environmental structure in FIGS. 2 and 6 is for illustrative purposes only and forms no part of the claimed design.
